UNITED STATES PATENT OFFICE

HARRY DRACHENBERG, OF CINCINNATI, OHIO

DESIGN FOR A COIN DRUG DISPENSER CABINET

Application filed July 3, 1931. Serial No. 40,404. Term of patent 14 years.

To all whom it may concern:

Be it known that I, HARRY DRACHENBERG, a citizen of the United States, residing at Cincinnati, county of Hamilton, and State of Ohio, have invented a new, original and ornamental Design for a Coin Drug Dispenser Cabinet, of which the following is a specification, reference being had to the accompanying drawing, forming a part thereof.

In the drawing, the figure is, a front perspective view of the coin drug dispenser cabinet, showing my new design.

I claim:

The ornamental design for a coin drug dispenser cabinet, as shown.

HARRY DRACHENBERG.
